[57] CLAIM

The ornamental design for the automobile window decal, as shown and described.

DESCRIPTION

FIG. 1 is a front elevation view of the automobile window decal of the present design;

FIG. 2 is a front elevation view thereof with the decal positioned on a window of the automobile with the automobile shown in broken lines, the broken line drawing is for illustrative purposes only and forms no part of the claimed design; and,

FIG. 3 is a perspective view thereof with the decal mounted on a rear window of an automobile with the rear window shown in broken lines, the broken line drawing is for illustrative purposes only and forms no part of the claimed design.

The decal is flat and having no substantial thickness.

The rear surface of the claimed design is flat and unornamented.
